HOLDER

Peter C. Brashear, Castleton-on-Hudson, N. Y.

Application September 26, 1931
Serial No. 565,383

9 Claims. (Cl. 131—10)

My invention relates to cigar and cigarette holders and more particularly to a device of this character which may readily be adjusted to receive and hold anything from a cigarette of the 5 smallest size to an ordinary or large size cigar.

One of the objects of my invention is to provide a unitary device of this character which may quickly and conveniently be adjusted by a simple manipulation thereof to receive and retain the 10 particular size of cigarette or cigar at hand. Another object is to provide a device of this character which can be made cheaply and yet will possess those characteristics of lightness, rigidity, utility and attractiveness of design which will make it 15 commercially acceptable.

With these objects in view my invention includes the novel elements and the combinations and arrangements thereof described below and 20 illustrated in the accompanying drawing in which—

Fig. 1 is an assembled view of my device;

Fig. 2 is a developed plan view of the element which directly holds the cigarette or cigar;

Fig. 3 is a plan view similar to Fig. 2 showing 25 the manner in which the rolling of the holding element is started;

Figs. 4 and 5 show the holding element in successive stages of the rolling;

Fig. 6 shows the element completely rolled to 30 accommodate ordinary cigarettes;

Fig. 7 shows the holding element rolled to accommodate a very small cigarette; and

Fig. 8 shows the holding element rolled to 35 accommodate a cigar.

Referring to the drawing my device comprises but two parts, a mouth piece element 1 and a holding element 2. The mouth piece element may be of wood, hard or soft rubber, Bakelite, quill or any other material or substance suitable 40 to the purposes intended, whether stiff or flexible. It is, generally speaking, tubular in form having an opening 3 at one end adapted to receive and frictionally engage the smaller end of the holding element, and it may be provided with the usual 45 enlargement 4 at the opposite end to provide a better grip thereon by the lips or teeth.

The holding element 2 is of paper, parchment, textile material, or any other substance which can 50 be made in sheet form and which possesses the essential flexibility to permit of its being rolled into the forms shown and, when so rolled, will have the requisite rigidity to serve the purpose for which it is intended. The holding element comprises a sheet of flexible material which, roughly speaking, 55 may be said to have a modified triangular form as

shown in Fig. 2. That is to say, the upper portion of the triangle 5 is truncated or cut off, the sides 6 and 7 are curvilinear instead of straight while the side 8 may be substantially straight. In the embodiment shown in Fig. 2, the major 60 portion 9 of the base 6 is preferably circular and is drawn from the center 10. In other words, that portion of the holding element included between the radii 11 and 12 is a portion of a developed conical surface. Since the holder when rolled is conical in form and it is necessary that it be open 65 at each end, it must be truncated so that, strictly speaking, it is frusto-conical rather than conical. Hence, the upper lefthand corner portion 13 of the sheet which forms the periphery of the upper base of the frustum is also preferably circular and is described from the center 10 and is, therefore, concentric with the portion 9 of the base 6. The side 8 is smoothly connected to the base 6 by the curve 14, and the edge 7, which is preferably 70 slightly curved, is connected to the base portion 6 by a curve 15. Beyond the point 16 and between this point and the curved edge 7 the sheet is preferably cut on a straight line 17 as shown in Fig. 2. The purpose of these various cuts and details 75 will be apparent as the description proceeds.

The forming of the holding element is begun by rolling so that the edge 14 substantially overlies the edge 6, as shown in Fig. 3, the size of the circular opening 18 thus formed at the base 85 of the holding element being adjusted to or started at the proper size to accommodate the cigar or cigarette at hand. As the rolling progresses, the holder will appear as shown in Fig. 4. It will be apparent, particularly from a consideration of Figs. 4 and 5, that if the upper portion of the holding element 2 were not cut off, that is to say if the edges 7 and 8 were continued to an intersection 22, a continued rolling 90 of the element 2 would completely close the small end of the cone. In other words, the holder would be a complete cone instead of a frustum, in which case there would be no opening throughout the holder and it would be impossible to draw smoke therethrough. It is desirable that the 95 holding element be truncated by a plane perpendicular to the axis thereof and this object is attained by making the portion 13 substantially concentric with the base portion 9. When the periphery of the upper base of the cone is substantially a complete circle, it is desirable in the further rolling of the sheet that the remaining unrolled portion should not extend to any considerable degree above the square truncated top 100 (see Fig. 5). Hence, the edge 17 is so cut 105 110

(see Figs. 5, 6, 7 and 8) that it forms on the exterior surface of the holding element a descending helix or spiral. From a consideration, particularly of Figs. 6, 7 and 8, it will be apparent that the base portion 6 of the developed holding element 2 forms a circular base for the conical holder and that the edges 15 and 7 form an ascending spiral or helix on the exterior surface of the holder. This helix ascends to the point 20 in a clockwise direction as viewed in Figs. 6 and 8, and from this point to the truncated upper base, the edge 17 forms a helix which ascends in a counter-clockwise direction. Thus, the upper or smaller end of the holding element is maintained open at all times irrespective (within the limits of the rolls for which the device is designed to accommodate) of the diameter of the opening at the large end of the holder. Having rolled the holder in this form it is inserted in the mouth piece element as shown in Fig. 1 to form a complete holder. Since the mouth piece frictionally engages the holding element and secures it in rolled, frusto-conical form it is quite apparent that the termination, 20, of the ascending helix should be near the upper base of the conical frustum whereby it may be secured by the mouthpiece.

When it is desired to adjust the holder to accommodate another size of cigarette or cigar the holding element is merely pulled from the mouth piece, unrolled and re-rolled to the proper diameter and inserted in the mouth piece. No adhesive is necessary to hold the sheet 2 in rolled position, and when formed as described above and inserted in the mouth piece, it will be found substantially air-tight and well suited for the purposes intended.

Referring particularly to Fig. 2 it will be noted that the portion of the element 2 included between the radii 11 and 12 is a development of that portion of the frusto-conical holder which includes the periphery of the lower base and a small portion of the periphery of the upper base. Adjacent this portion is that forming the periphery of the upper base including a point on the lower base, and that forming the spiral wrapping about the two first mentioned portions. The triangular portion to the left of radius 12 forms a tab or part for starting the rolling operation.

While I have described my invention in its preferred embodiment, it is to be understood that I am not strictly limited to the details of construction which I have described at some length merely for the purpose of clearness. For example, the essential features of my invention are a holder of flexible material which can be conveniently rolled to various sizes as shown in the drawing, and which when so rolled will form a hollow frusto-conical element in which the opening at the smaller end will be of such size as not to interfere with the draft therethrough. It will be evident from a consideration of Figs. 5, 6, 7 and 8 that the angular relation between the edges 17 and 7 may be varied considerably and yet not effect a closure or an appreciable reduction in the size of the opening at the small end of the holder. That is, it will be quite apparent that the spiral or helix formed by the edge 7 may extend to a much greater height in a clockwise direction than is shown in the drawing.

What I claim is:

1. In a holder of the character described, the combination with a holding member comprising a hollow conical frustum open at each end and formed of a sheet of flexible material, a portion

of an edge of said sheet forming the periphery of the lower base of said frustum, another edge of said sheet forming the periphery of the upper base of said frustum, and an edge intermediate said edges forming an ascending conical helix on the outer surface of said member, of a mouth piece element provided with an opening at one end frictionally engaging the smaller portion of said frustum and securing said sheet in frusto-conical form. 80

2. In a holder of the character described, the combination with a holding member comprising a hollow conical frustum open at each end and formed of a sheet of flexible material, a portion of an edge of said sheet forming the periphery of the lower base of said frustum, another edge of said sheet forming the periphery of the upper base of said frustum, and an edge intermediate said edges forming an ascending conical helix on the outer surface of said member and terminating at a point below the upper base of said member, of a mouth piece element provided with an opening at one end frictionally engaging the smaller portion of said frustum and securing said sheet in frusto-conical form. 85

3. In a device of the character described, the combination with a hollow, frusto-conical holding element consisting of a roll of flexible material, of a tubular mouth piece element frictionally engaging the smaller end of said roll and securing said flexible material in frusto-conical form. 90

4. In a device of the character described, the combination with a frusto-conical holding element consisting of a single sheet of flexible material the development of which comprises a portion forming a complete frustum of a cone and a contiguous portion forming a spiral wrapping about the exterior of said frustum and terminating near the upper base thereof, of a tubular mouth piece frictionally engaging the smaller end of said frustum and the terminal portion of said wrapping and securing the whole in assembled relation. 105

5. A cigarette holder comprising a frusto-conical holding member formed of a roll of flexible material, the edges of the outer layers of said roll lying in spirals about the surface of said member and the end of said roll terminating near the smaller end of the frustum; and a tubular mouth-piece element extending over and engaging the smaller end of the frustum and overlying the end of said roll to an extent adapted to hold the same against the underlying surface of the holding member. 110

6. In a holder of the character described, including a tubular mouthpiece, a frusto-conical holding element comprising an integral sheet of flexible material approximating in form a slightly truncated right triangle having a hypotenuse and two curvilinear legs differing substantially in length; the shorter leg joining with the hypotenuse and approximating in its curvature throughout the major portion thereof a circle having its center beyond the limits of said sheet and a radius approximating the length of an element of the cone of which the holding element is a frustum. 115

7. In a holder of the character described, including a tubular mouthpiece element, a frusto-conical holding element comprising an integral sheet of flexible material approximating in form a slightly truncated right triangle having legs of substantially different length, the shorter of said legs being curvilinear throughout with its major portion approximating a circular arc having a radius equal to an element of the cone of which the 120

holder is a frustum and forming the base of said frustum.

8. In a holder of the character described, including a tubular mouthpiece, a frusto-conical holding element comprising an integral sheet of flexible material approximating in form a slightly truncated right triangle having legs of substantially different length, the shorter of said legs being remote from the truncation and curvilinear throughout with its major portion approximating a circular arc having a radius equal to an element of the cone of which the holder is a frustum; and the truncated edge including a substantially

straight portion and a curvilinear portion approximately concentric with the shorter of said legs.

9. A cigarette holder comprising a frusto-conical holding member formed of a roll of flexible material, the edges of the outer layers of said roll forming an ascending spiral on the surface of said member terminating near the smaller end of the frustum; and a tubular mouthpiece element embracing the smaller end of said roll and overlying the outer end of the rolled material. 80 85
